RAMMER FOR COMPACTING SAND IN MOLDS.

1,316,973.

Specification of Letters Patent. Patented Sept. 23, 1919.

Application filed November 22, 1916. Serial No. 132,751.

To all whom it may concern:

Be it known that I, NICOLAS RAPPEZ, a subject of the King of Belgium, residing at Haine, St. Pierre, in the Kingdom of Belgium, have invented certain new and useful Improvements in Rammers for Compacting Sand in Molds, of which the following is a specification.

My invention relates to a rammer for compacting sand in molds. One object of my invention is to provide a rammer of simple and practical construction, adapted to secure a technically perfect compacting of the sand in the mold or in other words to secure a more or less important compacting of the sand at given places of the mold while maintaining a certain porosity at other places in order to permit the escape of the gas and to facilitate the shrinkage of the metal when it cools.

Another object of my invention is to provide a rammer which will be especially adapted for the manufacture of castings in series, that is to say securing always the same action in different molds used successively and at the same predetermined places in said molds.

With these objects in view, my invention essentially consists in certain new combinations and arrangements of parts which will be hereinafter fully described and pointed out in the appended claims.

In the annexed drawing which shows as an example one embodiment of my invention in its application to the molding of a given casting,

Figure 1 is a side elevation of the new rammer.

Fig. 2 is a side elevation showing separately the piece which is to be molded, a wheel in the present instance.

Fig. 3 is a top view, corresponding to Fig. 1 showing, as an example, how the several elements of the rammer are arranged, in the example chosen, in order to correspond to the shape of the pattern which is to be molded.

a is a supporting member such as a plate or disk, which can be massive, hollowed or of any other form. *b* are rods or bars which are rigidly attached to the supporting member *a*. Each of the said bars is provided or formed at its lower end with a ramming head *c*, the form of which varies

according to the place of the mold which is to be acted upon; said ramming heads *c* can also be circular in shape as it is shown in *c*¹ when they have to act in an angle, for example, or square as it is shown at *c*², rectangular as shown at *c*³ or trapezoidal as *c*⁴ or of any other shape according to the shape of the several parts of the pattern which is to be molded.

The rods or bars *b* have different lengths as it is shown in Fig. 1, according to the relief of the several parts of the pattern model *d*, the longest rods corresponding to the parts of the model which have the minimum of relief and the shortest rods corresponding to the part of the pattern, such as *d*¹, for instance, having the greatest relief or the greatest height.

Said rods *b* are attached to the plate or disk *a* and are spaced from one another according to the necessities of the molding operation; their number varies according to the shape of the pattern so as to secure, at all the places where they have to act upon the sand, a convenient compacting of said sand in the mold box against the several faces of the pattern.

To make use of a rammer composed as described, the pattern being placed in a mold box in a well-known manner, sand is placed in the mold box to the required height; an alternative movement in vertical direction, that is to say an up and down movement is then given to the plate *a* so as to cause the ramming heads *c* to strike on the sand contained in the mold box. This up and down movement can be produced manually or mechanically according to the dimensions of the apparatus; to this end, the plate *a* may be provided with a bar *e* adapted to be grasped by hand or to be fixed in a suitable actuating machine.

As a consequence of the up and down movement, all the ramming heads *c* act simultaneously by percussion or by pressure, thus compacting the sand in the mold box.

As it will be obvious, in such conditions, a rammer combined for a given pattern will suit for the molding of a multiplicity of pieces of the same pattern or in other words can be used for compacting successively the sand in a series of mold boxes without possibility that any difference whatever be pro-

duced from one mold box to the other, under the only condition that the pressure exerted on the plate *a* be the same in each operation.

5 The rods *b* are preferably fixed or attached to the plate *a* so as to be removable in such a manner that with an appropriate number of sets of rods *b*, having variable lengths and ramming-ends *c* of variable shape, all the necessary combinations can be realized to suit the several cases which can be encountered in practice. The rammer composed for the molding of a given pattern may then be employed, without any 10 modification or adjusting, for the molding of an infinity of pieces of the same pattern.

The rammer described has the advantage to secure a uniform compacting action always at predetermined places, a result 20 which cannot be obtained with the devices hitherto used, for instance with the ramming plates, (plane or embossed) which generally produce a greater compression at the upper part of the mold and do not allow 25 of maintaining at given places the necessary porosity to assist the escape of the gas during the casting, and the shrinkage of the metal during its setting.

It also has the advantage over the hand- 30 rammers, power-rammers, pneumatic rammers and the like to avoid the necessity of causing the rammers to act successively on the several parts of the mold. In this case, as it is well known, the blows are rarely 35 struck exactly where they ought to be struck and frequently they are struck so badly that they cause the alteration and affect the solidity of the pattern which must be repaired or renewed if the danger of producing 40 altered castings will be avoided. Such inconveniences cannot be encountered with a device as described, each ramming head *c* of a given rod *b* acting evidently always at a predetermined place.

45 I am aware that the use of ramming rods cooperating with a common support is not new in devices of this kind; in the devices already known, however, the rods had always the same length and the ramming 50 heads at their ends, had all the same shape; said rods further were acting only under the action of their proper weight and their action upon the sand was the same on all the places of the mold box, the common sup- 55 port for said rods serving only as a guid-

ing device and to produce their common upward movement.

Such a construction does not allow, like that according to my invention, a technically perfect compacting of the sand in the 60 mold box, if it is considered that, in order to avoid flaws and cracks or other defects, it is necessary that for each given piece, the compacting be more or less important at given places while a certain porosity is 65 maintained at other places to allow the escape of the gas and to permit the shrinkage of the metal during its cooling. Devices of this kind, further do not secure an identical action from one mold to another as there 70 is no guarantee whatever that the action of the ramming heads will always be the same at the same places.

What I claim is:

1. In a rammer, a support, a plurality of 75 ramming elements mounted on said support reproducing in outline the casting to be formed, said ramming elements comprising rods of varying lengths, heads at the ends of said rods, said heads having varying 80 angular and circular shape, the shape of the heads and lengths of the rods depending upon the pattern around which the sand is to be tamped, certain of said ramming elements being spaced apart relative to one another and of shorter length than called for by the pattern at certain places in the pattern where definiteness of design may be sacrificed, there to provide a porous zone for the escape of gas during casting and to 85 facilitate the shrinking of the metal when it cools.

2. In a rammer, a support, a plurality of 90 ramming elements mounted on said support, reproducing in outline the casting to be formed, certain of said ramming elements being spaced relative to one another and of shorter length than called for by the design to provide a porous zone at such places where definiteness of design may be sacrificed, there to provide for the escape of the 95 gas during casting and to facilitate the shrinking of the metal when it cools. 100

In testimony whereof I have affixed my signature in presence of two witnesses.

NICOLAS RAPPEZ.
